SLAP-JACK FIGURE TOY

Willis Martin Lakin, Chicago, Ill., assignor to Marlin Electric Company, Chicago, Ill., a corporation of Illinois

Application July 9, 1956, Serial No. 42,168

Term of patent 14 years

(Cl. D34—15)

Fig. 1 is a front perspective view of a slap-jack figure toy, showing my new design in one position;

Fig. 2 is a front elevational view thereof, to reduced scale, in another position;

Fig. 3 is a side elevational view thereof, to reduced scale, in another position;

Fig. 4 is a top plan view thereof to reduced scale.

I claim:

The ornamental design for a slap-jack figure toy, as shown.
